UNITED STATES PATENT OFFICE.

BENJAMIN F. JAMES, OF ROCKLAND, ONTARIO, CANADA.

CYLINDER-GRINDER ATTACHMENT FOR LATHES.

Application filed September 5, 1922. Serial No. 586,309.

To all whom it may concern:

Be it known that I, BENJAMIN F. JAMES, a citizen of the Dominion of Canada, and resident of Rockland, in the county of Russell and Province of Ontario, Dominion of Canada, have invented certain new and useful Improvements in Cylinder-Grinder Attachments for Lathes, of which the following is a specification.

10 This invention has relation to certain new and useful improvements in a cylinder grinding attachment for lathes and has for its primary object the provision of an attachment of the character stated which will be of simple and inexpensive construction and may be readily attached to lathes of conventional form without material alterations therein.

20 The invention has for another object the provision of an attachment of the character stated which will be of such construction and operation that the grinding member may be rotated at various speeds in an eccentric member and the latter adjusted so as to vary the throw thereof, as desired.

25 The invention has for a further object the provision of a lathe attachment of the character stated in which will be included a rotatable shaft carried in an eccentric member 30 adjustable in a second eccentric member which is rotatable at a speed different from the speed of rotation of the shaft and which shaft carries the grinding member.

35 A further object of the invention resides in the provision of a lathe attachment of the character described which will be of simple and compact construction and in which the adjustable parts may be readily adjusted and held in their adjusted positions during operation of the lathe attachment.

40 A still further object resides in the provision of a grinding attachment for a lathe in which the power transmitting members of the attachment are supported in a swinging frame so as to automatically adjust the tension of the driving belts and chains as the parts of the attachment are adjusted to regulate the throw of the eccentric members.

45 The invention has for a still further object the provision of a lathe attachment of the character set forth which will be of such construction and operation that the eccentric members thereof may be readily adjusted with respect to one another so as to regulate the size of the arc in which the grinding member travels and thereby con-

trol the depth of grinding in the sides of the cylinder in which the grinding operation is being performed.

50 With the foregoing and other objects in view as will appear as the description proceeds, the invention consists in the novel construction, combination and arrangement of co-operating elements as hereinafter more specifically set forth, claimed and shown in 55 the accompanying drawings forming a part of the present application, in which:

Fig. 1 is a fragmentary side elevation of a lathe with the improved grinding attachment mounted thereon.

70 Fig. 2 is an end elevation of the parts shown in Fig. 1.

75 Fig. 3 is a transverse section through the lathe and looking toward the attachment mounted thereon, the shaft for the grinding wheel being shown in transverse section.

80 Fig. 4 is a detail longitudinal vertical section substantially on the plane of line 4-4 of Fig. 3, looking in the direction indicated 85 by the arrows.

85 Referring more in detail to the drawings in which similar reference characters designate corresponding parts throughout the several views, 10 designates in general the lathe body or frame supported on the legs 11. The attachment is mounted on one end of the lathe body or frame 10, as will be readily seen by referring to the drawings. The main power belt 12 for the lathe is engaged 90 around the belt wheel 13 on the shaft 14. This shaft 14 also carries a belt wheel 15 and sprocket wheel 16, the purpose of which will presently appear. A depending bearing frame 17, of substantially U-shape is 95 provided for the shaft 14 and the latter is extended through the upstanding legs of the depending bearing frame 17 on opposite sides of the belt wheels 13 and 15 and the sprocket wheel 16.

100 A swinging bearing frame 18 of substantially U-shaped form is loosely mounted by the rear ends of its legs on the shaft 14 so as to straddle the belt wheels 13 and 15 and the sprocket wheel 16, as shown in Fig. 105 1. The swinging bearing frame 18 extends forwardly at the end of the lathe body or frame 10. A comparatively large belt wheel 19 and a comparatively small belt wheel 20 are mounted on the shaft 21 positioned 110 transversely in the forward end portion of the swinging bearing frame 18, as shown in

Fig. 2. The comparatively small belt wheel 20 is positioned opposite the belt wheel 15 which is a comparatively large belt wheel while the belt wheel 13 is a comparatively small belt wheel. A drive belt 22 connects the comparatively small belt wheel 20 with the comparatively large belt wheel 15 in order that the latter may drive the comparatively small belt wheel 20 and thereby 5 rotate the shaft 21 at a greater speed than the shaft 14. A drive belt 23 operates around the comparatively large belt wheel 19 and around a comparatively small belt wheel 24 on the shaft 25 to rotate the latter 10 at a greater speed than the shaft 21. The shaft 25 will be later more clearly described. The sprocket chain 26 works around the sprocket wheel 16 and also around a corresponding sprocket wheel 27 on the stub 15 shaft 28 parallel with the shaft 25 and below the latter, as shown in Figs. 1 and 2. The stub shaft 28 also carries a small sprocket wheel 29 around which the sprocket chain 30 operates to drive the large sprocket 20 wheel 31 at a reduced speed, the sprocket chain 30 being operatively engaged around the large sprocket wheel 31, as clearly shown 25 in Figs. 1 and 2.

By referring particularly to Fig. 4, it 30 will be seen that the large sprocket wheel 31 is formed on the removable outer head or plug 32 for the main rotatable cylinder 33, set screws 34 or other suitable members 35 being employed at the outer end of the main rotatable cylinder 33 to retain the removable outer head or plug 32 in position with the eccentric opening 35 of the removable outer head or plug 32 registering with the corresponding eccentric longitudinal passage 36 of the main rotatable cylinder 33. This eccentric longitudinal passage 36 extends entirely through the main rotatable cylinder 33 and both this eccentric longitudinal passage 36 and the eccentric openings 35 are of circular form. The eccentric opening 35 and eccentric longitudinal passage 36 are of sufficient diameter to extend from a point above the longitudinal center of the main rotatable cylinder 33 and the 40 removable outer head or plug 32 thereof, to a point near the bottom thereof when the main rotatable cylinder 33 is in the position shown in the drawings. This will be more clearly understood as the description 45 proceeds.

The ends of the main rotatable cylinder 33 are mounted for rotation in the supporting bearings 37 which are mounted on the upstanding ends 38 of the substantially U-shaped supporting member 39. The supporting legs 40 for the substantially U-shaped supporting member 39 depend from the main portion thereof and rest upon the longitudinal side members of the lathe body 60 or frame 10, as shown clearly in Fig. 3,

thereby spacing the main rotatable cylinder 33 a considerable distance above the lathe body or frame 10. Clamping bolts 41 are extended upwardly through the plate 42 positioned in the lathe body or frame 10 70 and the upper threaded ends of the clamping bolts 41 extend through the main portion of the substantially U-shaped supporting member 39 to receive the clamping nuts 43, as shown clearly in Fig. 1. Upper bearing members 44 for the main rotatable cylinder 33 are extended transversely over the latter and have outturned ends 45 secured upon the supporting bearings 37 to either side of the main rotatable cylinder 33, by 80 suitable securing members 46. It is to be understood that the supporting bearings 37 have arcuate recesses to receive the main rotatable cylinder 33 and the upper bearing members 44 are of arcuate form, so as to provide for proper mounting of the main rotatable cylinder 33. Suitable lubricant cups 47 are mounted on the upper bearing member 44, as shown in the drawings, in order that the main rotatable cylinder 33 85 may be properly lubricated at all times for free rotation within the supporting bearings 37 and upper bearing members 44.

Positioned in the eccentric longitudinal passage 36 of the main rotatable cylinder 33 and the eccentric opening 35 of the removable outer head or plug 32 of the main rotatable cylinder 33 is the secondary or inner cylinder 48 which is of sufficient length to project at one end past the removable outer head or plug 32, while the other end of the secondary or inner cylinder 48 projects past the corresponding end of the main rotatable cylinder 33. This may be readily understood by referring to Figs. 1 and 4. The secondary or inner cylinder 48 has a longitudinal circular passage 49 extending its entire length and arranged eccentrically therein. The grinding wheel operating shaft 25, previously mentioned, extends through and rotates in the longitudinal circular passage 49. While this grinding wheel operating shaft 25 has been previously mentioned just as a shaft it will now be termed the grinding wheel operating shaft 25. A cap 50 is mounted on the extended rear end of the secondary or inner cylinder 48 and secured in position by suitable set screws 51, as shown in Figs. 1 and 2, or by other suitable means. In Fig. 4 the comparatively small belt wheel 24, previously mentioned, is shown as being keyed to the grinding wheel operating shaft 25 and having an enlarged inner end 52 adjacent the outer face of the cap 50. A suitable packing 53 is provided around the grinding wheel operating shaft 25, immediately inward of the cap 50. A packing 54 is also provided around the grinding wheel operating shaft 25 at the forward end of the sec- 100 105 110 115 120 125 130

secondary or inner cylinder 48. It will also be seen by referring to Figs. 1, 3 and 4 that a segmental gear wheel 55 is secured to the forward end of the secondary or inner cylinder 48 by suitable securing members 56, the grinding wheel operating shaft 25 passing through the segmental gear wheel 55, as shown in Fig. 4 with a collar 57 located on the grinding wheel operating shaft 25 adjacent the forward face of the segmental gear wheel 55. Engaged with peripheral teeth 58 extending around a portion of the segmental gear wheel 55 is an adjusting worm screw 59. This adjustable worm screw 59 is mounted in suitable bearings 60 on the forward end of the main rotatable cylinder 33 and an operating wheel or head 61 is carried on one projecting end of the adjusting worm screw 59. It is evident that by means of the operating wheel or head 61, the adjusting worm screw 59 may be readily rotated to turn the secondary or inner cylinder 48 within the main rotatable cylinder 33 and thereby change the position of the grinding wheel operating shaft 25 with respect to the longitudinal axis of the main rotatable cylinder 33 and as a result of this adjustment vary the throw of eccentric movement of the grinding wheel operating shaft 25 as the main rotatable cylinder 33 is rotated. An outer shaft section 62 of a smaller diameter than the grinding wheel operating shaft 25 is extended forwardly thereof and in alignment with the grinding wheel operating shaft 25, said outer shaft section 62 being connected with and operated by said grinding wheel operating shaft 25. The grinding wheel 63 of conventional form is suitably mounted on the free forward extremity of the outer shaft section 62, as shown in Fig. 1.

By referring to the drawings, it will be seen that the stub shaft 28 rotates in the upstanding end 38 of the supporting member 39 at the end of the lathe body or frame 10 and in the supporting bearings 37 carried on said upstanding end 38. It will also be evident that the grinding wheel operating shaft 25 is rotated at a rapid rate of speed while the main rotatable cylinder 33 is rotated in the same direction at a considerably reduced speed, this main rotatable cylinder 33 carrying with it the secondary or inner cylinder 48 and the grinding wheel operating shaft 25. While the main rotatable cylinder 33 always rotates in the same circle and the circle in which the secondary or inner cylinder 48 rotates is always the same within the first circle, the path of movement of the grinding wheel operating shaft 25 with respect to the longitudinal axis of the main rotatable cylinder 33 is determined by the position of the secondary or inner cylinder 48 within the main rotatable cylinder 33. This may be understood by reference to Figs. 2, 3 and 4. By referring to Figs. 1, 2 and 3 it will be seen that the depending bearing frame 17 includes a long leg 17' at the side toward the end of the lathe body or frame 10. The upper end of the long leg 17' is secured to the rearwardly extended portion 64 of one of the upstanding ends 38 of the supporting member 39. Both of the upstanding ends 38 of the supporting member 39 are extended rearwardly and the rearwardly extended portions 64 are connected by the rear connecting plate 65 secured thereto by suitable securing members 66.

It is believed the complete construction and operation of the lathe attachment should now be apparent from the foregoing paragraphs taken in connection with the accompanying drawings without further detailed description. It may be briefly stated, however, that whenever the work is properly supported opposite the main rotatable cylinder 33 and fed to the grinding wheel 63, the attachment may be adjusted and operated to cause proper action of the grinding wheel 63 on the work. For example, if a rapid rotation of the grinding wheel 63 is all that is desired, the secondary or inner cylinder 48 is adjusted through the medium of the adjusting worm screw 59 to support the grinding wheel operating shaft 25 in the centre of the main rotatable cylinder 33. In such a case, the main rotatable cylinder 33 will rotate slowly around the grinding wheel operating shaft 25 without having any effect upon the latter. If preferred, the rotation of the main rotatable cylinder 33 may be discontinued.

Whenever it is desired to cause a movement of the grinding wheel operating shaft 25 in a circle greater than the circumference of the grinding wheel operating shaft 25, the secondary or inner cylinder 48 is turned or adjusted in the main rotatable cylinder 33 until the grinding wheel operating shaft 25 is thrown off of the centre of the main rotatable cylinder 33 a sufficient distance to cause a movement of the grinding wheel operating shaft 25 in a circle of the desired size concentrically of the longitudinal axis of the main rotatable cylinder 33 as said grinding wheel operating shaft 25 and said main rotatable cylinder 33 are rotated at their respective speeds. This double motion of the grinding wheel operating shaft 25 is provided for by simple operation of the adjusting worm screw 59 to position the grinding wheel operating shaft eccentrically of the main rotatable shaft 33. The double motion of the grinding wheel operating shaft 25 is particularly desirable when grinding cylinders of the Ford and other motors, so as to evenly grind the entire inner walls thereof and increase the efficiency of operation of the engine. It is also evident that

the swinging bearing frame 18 permits of adjustment of the secondary or inner cylinder 48 and the grinding wheel operating shaft 25 within the main rotatable cylinder 33 and proper operation of the grinding wheel operating shaft 25 in its various positions without breaking or straining the operative connections between said grinding wheel operating shaft 25 and the shaft 21.

10 The weight of the swinging bearing frame 18 and the parts mounted therein will assure retaining of the swinging bearing frame 18 in proper position at all times.

While the preferred embodiment of the invention has been disclosed, it is to be understood that minor changes in the details of construction, combination and arrangement of co-operating elements may be resorted to

within the scope of what is claimed without departing from the spirit of the invention. 20
What I claim as new is:

In a device of the character stated, a shaft, means for imparting rotary movement thereto, a rotatable cylinder having an eccentric longitudinal passage therethrough, a head 25 for said cylinder having an eccentric opening coincident with said passage, a second cylinder mounted in said eccentric passage and opening and extended beyond said head and having an eccentric longitudinal passage 30 and receiving said shaft, a segmental gear on said second cylinder, and means cooperating with said gear wheel.

In testimony whereof, I affix my signature.

BENJAMIN F. JAMES.
